UNITED STATES PATENT OFFICE.

EDWARD N. MOOR, OF OAKLAND, CALIFORNIA.

TRAVERSE-MACHINE FOR LATHES.

1,112,716.

Specification of Letters Patent.

Patented Oct. 6, 1914.

Application filed March 17, 1914. Serial No. 825,249.

To all whom it may concern:

Be it known that I, EDWARD N. MOOR, a citizen of the United States, residing at Oakland, in the county of Alameda and State of California, have invented certain new and useful Improvements in Traverse-Machines for Lathes, of which the following is a specification.

My invention relates to the general class 10 of lathe-attachments and particularly to traverse-machines adapted for such work as gear-cutting, milling, indexing, drilling, grinding, etc. My invention is particularly adapted for and is applicable to that general 15 type of these traverse attachments of which the machine patented by me September 23, 1913, No. 1,073,698, is an illustration, and my invention, in a sense, may be considered as an improvement on said machine, the 20 general object of the improvement being to adapt said machine for a variety of conditions and uses thereby making it more efficient.

To this end my invention consists in the 25 novel machine and in the construction, arrangement and combination of its parts which I shall now fully describe by reference to the accompanying drawings, in which—

Figure 1 is a front elevation of my machine. Fig. 2 is an end view of the same. Fig. 3 is an elevation showing the worm gearing. Fig. 4 is an elevation of my machine showing the spindle and its connections turned to a position parallel with the stock. Fig. 5 is a longitudinal section of the spindle carrier. Fig. 6 is an elevation of my machine showing the use of a stepped pulley for variable speed driving. Fig. 7 is an end 40 elevation of Fig. 6. Fig. 8 is a fragmentary view showing the spindle pulley. Fig. 9 is an elevation of my machine showing the use of an index plate and index pin. Fig. 10 is an elevation, partly in section, of the 45 same, taken at right angles to the elevation of Fig. 9.

1 is a rigid column which forms the stock of the machine. This column has passed through it longitudinally a bolt 2, the lower 50 end of which has a foot flange 3 and its upper end a nut 4, bearing upon a cap 5 on the column head. By means of the foot-flange 3 the stock 1 is fitted to the lathe tool-post support in the usual manner and is 55 clamped thereto by the bolt 2 and nut 4.

About the column-stock 1, on a spline or

feather 7 thereon, is fitted the split sleeve 8 adapted for lineal adjustment on the stock, and to be rigidly fixed by means of bolts 9 through its ears 10. The sleeve 8 when loosened is adjusted lineally by a screw 11, with a handle 12 on its top, said screw being seated in a lug 13 projecting from the cap 5. The screw is threaded through a nut 15 of the sleeve 8. 65

The sleeve 8 is formed with a circular bearing face 16 having a central boss 17, and an annular T-shaped slot 18. To the circular bearing face 16 is fitted the flange-body 19 of the spindle carrier 20. The fitting is one which will permit the angular adjustment of the spindle carrier relatively to the bearing face 16 of the sleeve 8, a pivotal connection being made by fitting the flange-body 19 rotatably upon the central 70 boss 17 of the bearing face 16. The connection is insured by a central bolt 21, and is rendered rigid in the various angular adjustments, by the three bolts 22 which have their heads fitted in the annular slot 18 of 75 said bearing face 16. The central bolt 21 and two of the bolts 22, flanking the central bolt, form a line of bolts which are made to serve the double purpose of holding the bearing face 16 and the flange body 19 together, and of serving to clamp the split spindle-carrier together at its meeting edges, 80 as shown clearly in Fig. 4.

23 is an arm which by means of a split foot-clamp 23' is rotatably fitted upon the 90 spindle housing 24 which is clamped in the spindle carrier 20. The arm is fixed in any angular position to which it may be adjusted, by means of a bolt 25 in its foot-clamp. The arm 23 is slotted at 26 in a radial line having the spindle carrier for a center. This arm 23 serves as a holder for 95 adjustably attaching various devices to be used in the many operations and positions of which the machine is capable. Thus in 100 Figs. 1, 2 and 3, I show this arm in connection with a spindle driving mechanism, adapted to be operated by an overhead countershaft.

27 is a plate which carries a short shaft 105 28, with a pulley 29 to receive the power. The shaft 28 has a worm 30. The plate 27 is carried by the arm 23, being clamped thereto and adjustable in the slot 26 thereof by the back plate 31 and the bolts 32 which 110 pass through and are adapted to move in said slot. The worm 30 engages with a

worm gear 33 on the spindle 34 of the machine. The adjustment of the shaft 28 provides for varied distances from the spindle axis and, therefore, for various diameters of gears whether of the worm or spur type. Also the angular adjustment of the arm 23 about the spindle housing serves as a belt tightener for the overhead belt.

As I have shown in Fig. 4, the spindle-carrier together with all its connections may itself be adjusted to various positions, as, for example, parallel with the stock, by turning its body flange relatively to the bearing face of the sleeve 8.

In Figs. 6, 7 and 8, I show the slotted arm 23 as having applied to it a belt and pulley transmission of the stepped-pulley type, for variable speed. In this case a stepped pulley 35 is carried on a short shaft 36, adapted to be adjusted in the slotted arm and fixed thereto by a nut 37. 38 is the belt from an overhead countershaft to a pulley 39 on the shaft 36. 39' is a belt from the stepped-pulley to a pulley 40 on the spindle 34.

In Figs. 9 and 10, I show the use of the slotted arm 23 in connection with an index pin 41 adjustably carried therein, as seen in Fig. 10, and an index plate 42 carried on the spindle 34.

The spindle housing 24 which is clamped in the spindle carrier 20 is shown in Fig. 5 as containing the spindle 34, with its pulley 40, the bushings 43, the chuck 44, and the draw-in rod 45 with its handle 46.

In the several figures, the tool of the spindle is shown with abrasive wheels 47, though it is to be understood that other tools may be substituted, according to the work, such, for example, as circular milling cutters, fly-cutters, drills and drill-chucks, etc.

I claim:—

1. A traverse machine for lathes comprising a stock with means for securing it to the lathe member; a member fitted to said stock for lineal adjustment thereon; a spindle-carrier carried by said member and angularly adjustable with relation thereto; a

spindle-housing clamped in the carrier, and having a tool-operating spindle therein; an arm carried by and radially extending from the spindle housing, said arm being angularly adjustable on said housing; devices adjustably carried by said radial arm; and devices carried by the spindle and coacting with the devices carried by the radial arm.

2. A traverse machine for lathes comprising a stock with means for securing it to the lathe member; a member fitted to said stock for lineal adjustment thereon; a spindle-carrier carried by said member and angularly adjustable with relation thereto; a spindle-housing clamped in the carrier, and having a tool-operating spindle therein; an arm carried by and radially extending from the spindle housing, said arm having an elongated lineal slot and being pivotally mounted for angular adjustment on said housing; devices carried by said arm and adjustable in the lineal slot thereof; and devices carried by the spindle and coacting with the devices carried by the radial arm.

3. A traverse machine for lathes comprising a stock with means for securing it to the lathe member; a member fitted to said stock for lineal adjustment thereon, said member having a circular bearing face; a split-carrier for the spindle, having a flange-body, a central bolt passing through the meeting edges of the split spindle carrier to clamp said carrier, said bolt also passing through the flange-body of the spindle carrier into the bearing face of the lineally adjustable member to pivotally connect said parts; and lateral bolts also clamping the spindle carrier and passing through the flange body into the bearing face and having a circular play in said face.

In testimony whereof I have signed my name to this specification in the presence of two subscribing witnesses.

EDWARD N. MOOR.
